UNITED STATES PATENT OFFICE.

WILLIAM L. SMYTH, OF VAN WIE'S, NEW YORK.

ICE-HARVESTING MACHINE.

SPECIFICATION forming part of Letters Patent No. 391,205, dated October 16, 1882.

Application filed December 16, 1881. Serial No. 258,067. (No model.)

To all whom it may concern:

Be it known that I, WILLIAM L. SMYTH, a resident of Van Wie's, in the county of Albany and State of New York, have invented 5 certain new and useful Improvements in Ice-Harvesting Machines; and I do hereby declare that the following is a full, clear, and exact description of the invention, that will enable others skilled in the art to which it appertains 10 to make and use the same, reference being had to the accompanying drawings, and to the letters of reference marked thereon, which form a part of this specification.

Similar letters refer to similar parts in the 15 several figures therein.

My invention relates to improvements in ice-harvesting machines; and it consists of the novel construction and combination of parts hereinafter described, and pointed out in the 20 claims.

The objects of the invention are made to appear in connection with the following description.

Figure 1 of the drawings is a side elevation 25 of my improved machine. Fig. 2 is a top plan view of the same. Figs. 3 and 4 are respectively front and rear elevations of the same.

My improved machine consists, essentially, 30 of a circular saw supported by a suitable frame and connected by intermediate gear-wheels and pinions with one or more drive-wheels which actuate the saw, whereby grooves and cross-grooves can be easily and quickly cut in 35 an ice field desired to be harvested, thereby facilitating the breaking up of the field of ice into cakes or pieces suitable for storage in ice-houses.

A is a rectangular frame, upon which are 40 bolted two pairs of uprights, A—one pair on each side. These uprights serve as guideways for the slide-boxes A², vertically reciprocatory therein. The slide-boxes receive the end bearings of the axle, upon which the traction drive-wheels W are fixed. The slide-boxes are also 45 provided on their upper side with an eyebolt, A³, to which the link A⁴ is pivoted at its lower end, the upper end of the link being pivoted to the component part A⁵ of a compound operating-lever. The part A⁵ is fulcrumed at one end to one of the uprights at A⁶, and the other end of the part is pivoted to the link A⁷,

which adjustably connects it with the other component part A⁸ of the compound lever, the link having adjusting holes A⁹. The component part A⁸ is fixed upon the shaft A¹⁰, rotary in boxes A¹², supported by the uprights A¹³, mounted upon the frame A. The shaft is provided with an operating-handle, A¹⁴, fixed thereon. The handle is provided with a detaining-hook, A¹⁵, pivoted thereon and adapted to hook onto the cross-bar A¹⁶ of the main frame. The main frame is also provided on each side with two supporting-runners, A¹⁷, adapted to support the whole machine during 60 transportation when the machine is not in use and when turning around upon the ice.

The traction-wheels are lifted from the ice to be supported by the main frame by means of the operating-handle and compound levers 70 connected with the slide-boxes A², as above described.

The traction-wheels are provided with spurs W, which engage with the ice and cause them to rotate when the frame is in motion.

Motion may be imparted to the frame by a horse hitched to the whiffletree W², secured to the forward end of the frame, or in any well-known manner. The main axle, to which the traction-wheels are fixed, supports centrally a 80 frame, B, pivoted thereon at or near its rear end.

The pivoted frame supports a train of gears and pinions adapted to engage with and be actuated by a driving gear-wheel, B², fixed 85 upon the main axle B³, to which are fixed the traction-wheels. The pivoted frame B also supports in suitable bearings at its forward end the rotary shaft B⁴, upon which is fixed a saw, B⁵.

The saw-shaft B⁴ is provided with a pinion, B⁶, adapted to engage with and be actuated by the above-mentioned train of gear-wheels and pinions, said train of gears and pinions consisting of the pinions B⁷, fixed upon the shaft 95 B⁸, the gear-wheel B⁹, pinion B¹⁰, gear B¹¹, and pinion B¹².

The forward end of the frame B is provided with the eyebolts C, fixed thereon and adjustably connected with the lever-arms C' by means 100 of links C², having the adjusting-holes C³. The lever-arms C' are fixed upon the shaft C⁴, rotary in boxes C⁵, supported by uprights C⁶, bolted to the main frame. The shaft C⁴ is pro-

vided with the lever-arm C⁷, fixed thereon and connected by rod C⁸ with an operating-lever, C⁹, pivoted at C¹⁰ upon a notched segment, C¹¹, secured to the main frame. The operating-lever is provided with a slide-dog, C¹², (shown by dotted lines in Fig. 1,) connected by wire C¹³ with operating-lever handle C¹⁴.

By means of the operating-lever C⁹ and connecting links and levers just described the forward end of the saw-supporting frame B can be raised or lowered to lift the saw from the ice or lower it to the depth to which it is desired to cut a groove in the ice.

When the saw is forced to the limit of depression to cut the deepest groove, the respective parts of the machine will occupy the respective positions shown in the several figures of the drawings, the controlling-lever C⁹ bearing against the shaft A¹⁰, the shaft acting as a stop to prevent the further depression of the saw. Should it be desired to cut a deeper groove, it is only necessary to connect the adjusting-links C² with the arm C¹ at one of the upper adjusting-holes, C³, which permits the saw-supporting frame to be depressed to a lower plane.

To facilitate the operation of raising and depressing the saw-supporting frame, I provide a counterbalancing-weight, D, adjustable upon the arm D', fixed upon the shaft C⁴.

The frame B will be partially balanced by the driver in occupying the seat S, mounted upon support S', secured to the rear end of the frame by bolt S². I also provide upon each side of the machine guide-blades F, secured to a bar, F', extending longitudinally of the main frame, one at each end of the respective bars. Each end of the bars is secured to one end of the cross-bars F², the other end of the cross-bars being pivoted to the central part of the main frame, or to a block, F³, supported centrally of the frame by the braces F⁴, bolted to the frame, as shown in Figs. 3 and 4. The bars F' are connected by chains F⁵ and rod F⁶ with the lever F⁷, pivoted thereon at F⁸, the chains running over pulleys F⁹, secured to the main frame. The levers F⁷ are pivoted at F¹⁰ upon lugs secured to the main frame.

When it is desired to raise the guides from the ice, it is only necessary to throw the upper end of lever F⁷ back and down upon the main frame, where it will be held by the tension upon the rods F', the pivot F⁸ occupying a lower plane than the pivot F¹⁰.

The operation of the machine is as follows: The respective parts being in the positions shown in the drawings, the machine is drawn along over the ice in an approximately straight line, which gives a rotary movement to the saw, cutting a groove of the required depth in the ice. After the groove has been cut of the re-

quired length, the lever A¹⁴ is drawn back to lift the traction-wheels from the ice, and the lever F⁷ thrown back and down upon the main frame to lift the guide-blade F from the ice. The machine is then turned around, riding upon the runners A¹⁷ in a position such that when the guide-blades are dropped upon the ice by throwing up the lever F⁷ the blades upon one side of the machine will drop into the groove just cut. The traction-wheels are then dropped upon the ice by releasing the lever A¹⁴, and the machine drawn back toward the starting-point in a direction parallel to the groove last cut, being maintained at the proper distance from said groove by the guide-blades therein. When the machine is again turned at the end of the second groove to cut the third groove, the operation of lifting and dropping the wheels and guide-blades is repeated, the guide-blades which were idle in cutting the second groove being brought into use by following in the second groove to determine the position of the third groove, and so on until the required number of grooves has been cut.

When desired, the main frame and runners may be dispensed with, and the machine, consisting of traction-wheels, saw, connecting gear-wheels, and frame, be drawn along by means of the latter frame.

What I claim as new, and desire to secure by Letters Patent, is—

1. In an ice-harvesting machine, a main frame provided with supporting-runners and upright slideways, in combination with traction drive-wheels provided with bearing-boxes adapted to slide in said slideways and connected with a rotary ice-saw by a train of gear-wheels and pinions, the said wheels and frame being provided with a system of levers for lifting the wheels from the ice and supporting them by the frame, substantially as described.

2. In an ice-harvesting machine having a main frame provided with supporting-runners and supports for the bearing-boxes of traction drive-wheels and a saw-supporting frame pivoted upon the axle of the traction drive-wheels, and a system of adjusting-levers adjustably connecting one end of the saw-supporting frame with the main frame, a counterbalancing-weight adjustable longitudinally of a supporting arm fixed upon said connecting mechanism and vibratory with the levers forming a part of said mechanism, substantially as described, and for the purposes set forth.

In testimony whereof I have hereunto set my hand this 15th day of December, 1887.

WILLIAM L. SMYTH.
